UNITED STATES PATENT OFFICE

2,150,509

ELECTRICALLY OPERATED PARKING
METER

Floyd R. Landrum, Dallas, Tex.

Application August 12, 1936, Serial No. 95,553

1 Claim. (Cl. 194—11)

This invention relates to a time parking meter and is particularly adapted for use in large cities for the purpose of allotting the time to different motorists who are tending to business in the 5 various sections of the down-town portion of said cities where the streets are narrow and the traffic is heavy and considerably congested. When in use, the meter is preferably positioned on a post or pedestal which is situated upon the curb and 10 where more than one meter is used they may be spaced at regular intervals or as otherwise desired.

A further object of the invention is to provide a new source of revenue for cities through utilization of the potential parking space in all available 15 streets and in addition provide sufficient space whereby each car may be parked in a convenient and orderly manner.

Another object of the invention is to provide means for restricting parking in congested business areas to those motorists having business in 20 said areas and further to reduce the number of parkers to those having only temporary business in that vicinity which co-incides substantially with the time limit provided by the meter.

A still further object of this invention is to improve this class of device and service so as to 25 increase its durability, efficiency and utility.

A further object of the invention is to provide a prominent indicating light as well as a graphic time dial whereby more pronounced designation 30 of the parking period provided or remaining is had.

Another important feature of the invention is the provision of two indicating lights of separate 35 and distinct colors which are readily visible from any direction. One of the lights such as red for indicating that the meter is not in operation and the other light such as green for indicating that the meter is in operation and also when there is 40 no light burning at all, it indicates that the meter is out of order for the reason that the electric current is not reaching said meter or some of its mechanical parts have become broken and need repair.

A further object of the invention is to provide 45 an electrically operated meter of the class described wherein the signal and time mechanism is automatic in its operation and of a positive and accurate nature with the obvious advantages and benefits.

Another object of the invention is to provide in 50 a coin actuated device, new and novel means for restricting the successful operation of the device to the use of specific coins thereby increasing the revenue to be had through the unsuccessful use

of slugs and the like or coins other than those intended to be used.

One of the important features of this invention is that it may be manufactured and constructed from any suitable materials of durability and that its arrangement and manufacture is simple and capable of efficient workmanship.

The accompanying drawing forms a part of this specification in which similar numerals of reference indicate corresponding parts in all of the figures of the drawing:

Explanation of figures

Figure 1 is a view partly in elevation and partly in section showing the working mechanism of the 15 invention as assembled in a case.

Figure 2 is an exterior elevation view of the invention as assembled in a unit and case with the upper portion of the signal light globe broken.

Figure 3 is a horizontal sectional view taken 20 on line 3—3 of Figure 2 showing locking and re-setting mechanism of the meter with the said mechanism dis-engaged from the meter dial.

Figure 4 is a view similar to Figure 3 showing the locking and re-setting mechanism in engagement with the meter dial for turning the same.

Figure 5 is a cross sectional view taken on line 25 5—5 of Figure 3, transversely of the locking mechanism.

Figure 6 is a perspective view of the locking 30 sleeve for the tumblers of the lock.

Figure 7 is a vertical sectional view taken of line 7—7 of Figure 1 showing the bearing connecting between the switch actuating arm and the peripheral cam face of the meter dial.

Figure 8 is a wiring diagram of the electrical 35 connections between the elements of the invention.

Construction

In the drawing, the numeral 1 indicates an 40 electric light globe, preferably of a vivid color such as red, which is mounted on the top of a case or housing A within a transparent glass bowl B, attached to the top of the case. Another electric light globe 2 preferably of vivid color which 45 is distinctive from that of globe 1 such as green, is likewise mounted on top of the case A and within the Bowl B. As best shown in Figure 8, these globes 1 and 2 and a two way mercury switch 3 are wired together for connection in an 50 electric circuit C in such a manner that the globes will be lighted alternately depending on the position of the switch.

As shown in Figure 1, the mercury switch 3 is within the case and has a trip arm 4 extend-

ing therefrom into a coin slot 5 whereby a coin inserted in said slot will engage the arm 4 and trip or tilt the switch 3. A spring 7 extends from the opposite side of the switch to that of the arm 4 into engagement with an adjustable screw 8 to provide an adjustable tension or balance for the switch.

As best shown in Figures 1 and 7, the switch trip arm 4 has a vertical yoke 9 extending upward therefrom and within which a roller bearing 10 is mounted for engagement under tension of the spring 7, with the periphery or cam edge 11 of a rotatable disc 12 whereby the rotation of said disc will cause the trip arm 4 to be raised or lowered in accordance with depressions 13 or projections 14 in the periphery of the disc and thereby actuate the mercury switch.

This cam disc is mounted on the shaft of a small electric motor 15 that is positioned within the case, and has a time dial 16 on its outer face. An arcuate opening 17 is provided in the case, opposite the dial, Figure 2, for visibility of the dial. As shown in Figure 8, the electric motor 15 is connected in the electric circuit to the light globe 2 so that when said light is burning the motor 15 is running and the dial rotating.

As best shown in Figures 3 to 7 inclusive, a lock 18 is mounted in the case opposite the disc 12 for use in manually resetting the disc as will hereinafter be explained. This lock is similar to the common rotating barrel type except that the usual irregular projecting lugs 19 of the barrel 20 are constructed and adapted to protrude only from one side of the barrel when in a locked position when the key 26 is withdrawn from the lock. In this way the lugs, when in a locked position, will extend within the longitudinal slot 21 of a sleeve 22 which encircles the barrel, and when in an unlocked position will be withdrawn in the barrel enabling said barrel to be rotated freely in the sleeve. The lock barrel 20 has a stud 23 at its inner end adapted for engagement within a hole 24 in the disc 12 for rotating the disc upon rotation of the lock barrel.

A coil spring 25 confined between the hub end of the lock barrel and the inner end of the lock housing maintains the lock in normal disengagement from the disc.

Operation

With the parts of the invention in the positions shown in full lines in Figure 1, the meter is not in operation and the electrical circuit is closed through the mercury switch to the red light 1.

Upon the insertion of the prescribed coin D in slot 5, the weight of the coin will overbalance the tension of the spring 7, sufficient to move the trip arm 4 and its connected parts to the positions shown in dotted lines, thus disengaging the roller 10 from the adjacent indentation 13 of the disc and freeing same for rotation upon operation of the electric motor 15.

With the depression of the arm 4 the mercury switch 3 is tilted breaking the electrical circuit to the red light 1 and closing said circuit to the green light 2, thereby indicating that the meter is in operation. Likewise, with the tilting of the switch, the electrical circuit is closed to the motor 15 starting operation of same and commencing rotation of the disc 12 and the dial 16 in a clockwise direction, Figure 1, at a regular hourly rate of speed. As the disc rotates the projec-

tion 14 will engage the roller 10 and thereby depress the arm 4 sufficient distance to enable the coin D to drop into a suitable collection box 26a.

As the arm 4 is freed from the weight of the coin, the roller 10 will re-engage with the disc under tension of the spring 7, continuing operation of the meter until the roller engages in the next depression 13 of the disc. As the roller engages in said depression, the arm 4 is raised under tension of the spring 7 to the position shown in full lines of Figure 1, whereupon the switch 3 is tilted, breaking the electrical circuit to the motor and the green light 2, and closing the electrical circuit to the red light 1 which is lighted to indicate that the meter is not in operation.

The depressions 13 and the projections 14 on the disc correspond in number with the number of time divisions indicated on the dial and are relatively positioned with such time divisions so that each operating sequence of the meter will coincide with each of the indicated periods.

It is pointed out that the tension of the spring 7 may be varied so that upon the insertion in the slot 5 of a coin or slug which is heavier than the coin provided for, the additional weight of the slug will depress the arm 4 sufficient to drop the slug in the box 26a immediately freeing said arm for return to its normal position with the roller re-engaged in the depression 13 and the meter remaining inoperative. If a coin or slug which is lighter than that provided for, such slug will have no effect on the arm but will remain in the slot supported by the arm until a second coin is deposited, under which condition the first coin will pass into the box and the effect of the second coin on the arm will be determined by its weight as described above.

Provision is made in this meter for the resetting of parts to a non-operating position with the use of a key, for obvious reasons and advantages such as the cancelling of unused parking time. In re-setting the meter the key 26 is inserted in the lock whereupon the barrel is freed for rotation. Pressure is then applied inwardly on the barrel as same is rotated to engage the stud 23 in the opening 24 of the disc. By continued rotation of the barrel and disc parts may be restored to their normal non-operating position. It is pointed out that by the proper positioning of the sleeve 22 of the lock 50 the key cannot be removed until the parts have been fully restored to their non-operating position.

What I claim is:

In an electrically operated parking meter, signal means indicating operating and dormant conditions of said meter, a rotatable disc carrying a chronometrical dial capable of manual setting, said disc having peripheral means for predetermining its period of rotation, electrical means for operating said disc, a coin chute, a coin actuated lever disposed for pivotal displacement, a spring for maintaining adjustable tension on said lever, a roller carried by said lever, a switch also carried by said lever, an electric circuit connecting said switch, signal and disc operating means when said lever is actuated by a coin and having engagement through the medium of said roller with the peripheral means of said disc to predetermine the periods of rotation of the latter.

FLOYD R. LANDRUM.
